MEANS FOR HEATING WITH WATER

Bo Folke Randel, San Diego, Calif., assignor to
 C. A. Dunham Company, Marshalltown, Iowa,
 a corporation of Iowa

Original application February 25, 1929, Serial No.
 342,423. Divided and this application April 1,
 1932, Serial No. 602,570

11 Claims. (Cl. 237—67)

This invention relates to the art of heating, and more especially to a new and improved means for heating with water, in which hot water from a boiler or other source of supply is delivered under pressure to a radiator or radiators or other heating system and is admitted to each radiator or other heating device through a suitable expansion valve, preferably operated by differential pressure. The pressure in the radiator or heating system is maintained sufficiently lower than the pressure of the hot water supply so that the heated water will expand into vapor form under this lower pressure, then condense back to liquid form in the radiator or heating system, the condensate passing through a thermostatic trap or traps to the vacuum pump and from the high pressure discharge of said pump back to the boiler or other source of supply.

This application is a division of my copending application Serial No. 342,423, filed February 25, 1929, in which the novel method of heating is claimed.

At the present state of development in the art of heating with water, hot water at a temperature of approximately 180° F. is delivered to the radiators and is discharged at approximately 155° F. The heat transfer per pound of water in circulation is therefore approximately 25 B. t. u. To increase this heat transfer it would be necessary to increase the temperature of the water and this is done in so-called closed systems, where the temperature is maintained at 250° F. or over. While this arrangement from a heat transfer standpoint is an improvement, allowing as it does for smaller pipes and more economical installations, it is however objectionable on account of the increase of the sensible heat of the radiators. The so-called "hygienic" temperature in a radiator is approximately 155° F. or less, and any increase of this temperature is objectionable.

In my improved system of heating, which is a combination of water, vapor and vacuum systems, I considerably increase the heat transfer over other water heating systems, and at the same time I retain the sensible temperature of the radiator within hygienic limits.

This improved method of heating is based upon the fact that heated water under pressure will immediately flash into steam when admitted into a space in which the pressure has been sufficiently reduced. Thus if water at a temperature of about 300° F. and under 55 pounds pressure is admitted into a space where a pressure of 25 inches of vacuum is maintained, it will flash into steam at a temperature of about 126° Fahrenheit.

heit. Now if the steam or vapor is recondensed in this space, by further cooling, to liquid form, the condensate leaving the space at the temperature of 126° F., the heat transfer would be 300 minus 126 or 174 B. t. u. per pound of water passing through. And while the temperature of the incoming water was 300° F., the sensible temperature in such space would be only about 126° F. The heat transfer would, therefore, be approximately seven times as much as in ordinary hot water heating systems.

The principal object of this invention is to provide an improved apparatus for heating with hot water, such as briefly described hereinabove and disclosed more in detail in the specifications which follow.

Another object is to provide an improved means for heating by means of a combination of water and steam, circulated in a closed heating system.

Another object is to provide an improved form of expansion valve for admitting the hot water to the radiators.

Other objects and advantages of this invention will be more apparent from the following detailed description of certain approved forms of apparatus particularly adapted for carrying out the principles of this invention.

In the accompanying drawings:

Fig. 1 is a diagrammatic elevation of the improved heating apparatus.

Fig. 2 is a longitudinal central section through one form of a differential pressure expansion valve used in this system.

Figs. 3 and 4 are views similar to Fig. 2 showing other modified forms of this expansion valve.

Fig. 5 is a partial transverse section, taken substantially on the line 5—5 of Fig. 4.

Fig. 6 is a transverse section taken substantially on the line 6—6 of Fig. 4.

Referring first to Fig. 1, at 1 is shown the boiler or generator which furnishes hot water to the system through supply main 2 provided with main control valve 3. The radiators shown at 4 and 4a are supplied with hot water from main 2 through the risers 5 and 5a. The hot water is admitted to radiators 4 and 4a through the separate inlet expansion valves 6 and 6a, these valves preferably being controlled by variations in the pressure differential between the hot water supply and the condensing space within the radiators. After passing through these expansion valves 6 and 6a into the radiators, which are kept under a lower pressure, the hot water flashes into vapor form within the condensing spaces. This vapor, on

meeting the colder surfaces of the radiator, condenses back to liquid form, the latent heat of condensation being given off by the radiators so as to heat the air within the building in which the radiators are positioned. The condensate passes out of the radiators through the thermostatic return traps 7 and 7a and pipes 8 and 8a into the return main 9.

The thermostatic traps 7 and 7a may be of the conventional type provided with thermostatic discs or bellows filled with a volatile liquid, said liquid vaporizing when subjected to steam temperature so as to close the outlet port. The traps will be adjusted to pass air and condensate but not to pass steam, the heat of the steam closing the port by the expansion of the discs or bellows.

The condensate passes through return main 9 and check valve 9a to the exhausting mechanism. This exhausting mechanism comprises the centrifugal pump 10 which delivers the water from the tank 10b at high velocity through ejector 10c with the suction chamber of which return main 9 communicates, producing a vacuum in the pipe 9 and a pressure in pipes 10d and 11. The water of the ejector jet, together with the condensate and air withdrawn through pipe 9, are delivered into tank 10b through the pipe connection 10h. The tank 10b is vented at 10a, allowing non-condensable gases to be discharged from the system. When the water level within tank 10b (indicated at 10g) reaches a certain height, float 10e will open valve 10f, permitting a part of the condensate to be returned to the boiler under pressure through pipe 11.

Before entering the boiler, this condensate is passed through an ejector 12, the action of this ejector 12 being to cause positive circulation through supply main 2 from the boiler outlet to the return inlet, thus keeping the water in supply main 2 at the high temperature maintained in boiler 1.

While only two radiators 4 and 4a are shown by way of example, it will be understood that a plurality of radiators may be supplied from the pipe loop 2 in the same manner.

It will be seen that in this system of heating with water it is desirable to provide a valve at the inlet of each radiator 4 and 4a, which will retain a certain pressure drop through the valve, permitting the liquid to expand and evaporate, and which will automatically open or close when this pressure differential increases or decreases.

Novel differential pressure expansion valves of this type are shown in Figs. 2, 3 and 4, the general principle of operation being similar in the three forms.

In this valve the differential pressure element is shown in disc form at 13 in Fig. 2, and in bellows form at 13a in Figs. 3 and 4. This differential pressure element is enclosed in a valve body 15, and the inside of said element connects through tube 14 with the outlet or low pressure end of the valve, the high pressure inlet of the valve being at 16.

The movable valve member is shown in Fig. 2 at 17 in cone form, in Fig. 3 at 17a, in disc form, and in Fig. 4 at 17b, in sleeve form. The sleeve 17b has ports 17c (see Fig. 5) which are opened or closed by the movement of the sleeve.

The differential element being totally enclosed in the valve body and being surrounded by the fluid under high pressure, with the tube 14 connecting the inside of this element with the low pressure outlet, it is seen that variations of pressure difference will affect this element, contract-

ing or expanding the same with the increasing or decreasing of this pressure differential, thus opening or closing the valve. It will also be seen that by moving the entire differential mechanism, including the differential element, tube 14 and valve disc or sleeve, any predetermined pressure differential may be established. The valve may thus be set for any desired drop of pressure from inlet to outlet, and this drop will then be permanent under any conditions of pressure on the high or low pressure sides. Thus if set at a 20 pound drop, the high pressure may be 30 pounds with the low pressure 10 pounds, and if high pressure should increase to 40 pounds, the low pressure will increase to 20 pounds, maintaining a drop of 20 pounds. Therefore, in this improved system of heating, any definite pressure may be maintained in the radiator, and any increase of such pressure will close the inlet valve by expanding the differential pressure element, thus maintaining a definite pressure drop.

In Fig. 2 I have arranged for hand-operation of this valve by means of a hand wheel 18, by which the position of the differential element may be varied to provide various differential pressures. In Fig. 3, I accomplish such variation by a screw 19, which will allow the operator to set the differential as desired. In Fig. 4, I provide a thermostatically operated bellows 22 filled with a volatile fluid to adjust this pressure differential, so that when a desired room temperature has been reached, expansion of fluid in this bellows will close the valve. In this case, I also show a so-called "packless" construction of valve, by means of the bellows 23. Thermostatic element 22 is enclosed in the open chamber 20 and may be adjusted by a screw 21.

The detailed construction of this differential pressure expansion valve may vary, and I may adopt any of the present conventional forms of valve seats, balanced or unbalanced, cone shaped, flat disc shaped, sleeve or piston type. The differential element may also be of any conventional form, disc style, single or multiple; bellows; piston; etc., and I do not desire to limit myself to any definite form of valve except as to the main form which is a movable differential element enclosed in the valve body, surrounded by the fluid under high pressure, the inside of said element being in communication with the low pressure discharge of said valve. As far as the broader features of this invention are concerned, it is not even necessary that a differential pressure control valve be used. It is only necessary that some form of pressure-reducing valve or similar device be used at the inlet of each radiator so that there will be sufficient drop in the pressure of the heated water admitted to the radiator to cause this water to flash into steam.

Though I have shown and described a particular construction, combination and arrangement of parts by way of example, I do not wish to be limited to this particular construction, but desire to include in the scope of this invention any equivalent form of apparatus coming within the scope of the following claims.

I claim:

1. In heating apparatus, a source of heated water under pressure, a radiator, an exhausting means for withdrawing condensate, unvaporized water and non-condensable gases from the radiator and lowering the pressure therein, a steam-trap at the outlet of the radiator to prevent the escape of steam therefrom, and means automatic-

- 5 cally controlled by the respective pressures existing in the source and in the radiator for introducing the heated water into the radiator in limited quantities whereby the pressure in the 5 radiator will be kept lower than the pressure of the heated water by an amount sufficient to cause a portion of the water introduced to be expanded into steam.
- 10 2. In heating apparatus, a source of heated water under pressure, a radiator, an exhausting means for withdrawing condensate, unvaporized water and non-condensable gases from the radiator and lowering the pressure therein, a steam trap at the outlet of the radiator to prevent the escape of steam therefrom, and means automatically controlled by the respective pressures existing in the source and in the radiator for introducing the heated water into the radiator in limited quantities whereby the pressure in the 15 radiator will be kept lower by a constant difference than the pressure of the heated water so that a portion of the water introduced will be expanded into steam.
- 20 3. In heating apparatus, a source of heated water under pressure, a radiator, an exhausting means for withdrawing condensate, unvaporized water and non-condensable gases from the radiator and lowering the pressure therein, a steam trap at the outlet of the radiator to prevent the escape of steam therefrom, means automatically controlled by the respective pressures existing in the source and in the radiator for introducing the heated water into the radiator in limited quantities whereby the pressure in the radiator will be 25 lower than the pressure of the heated water by an amount sufficient to cause a portion of the water introduced to be expanded into steam, and thermostatic means cooperating with the last-mentioned means to cut off the flow of heated water to the radiator when a predetermined temperature has been reached in the space being heated by the radiator.
- 30 4. In heating apparatus, a source of heated water under pressure, a radiator, an exhausting means for withdrawing condensate, unvaporized water and non-condensable gases from the radiator and lowering the pressure therein, a steam trap at the outlet of the radiator to prevent the escape of steam therefrom, a conduit connecting the radiator with the source of heated water, a reducing valve in the conduit at the inlet to the radiator, and means for automatically operating the valve to maintain a predetermined pressure drop between the pressure of the heated water and the fluid pressure within the radiator.
- 35 5. In heating apparatus, a source of heated water under pressure, a supply pipe leading from the source, a plurality of radiators, branch supply conduits leading from the supply pipe to each of the radiators, a return conduit having branches leading from each of the radiators, a steam trap at the outlet of each radiator to prevent the escape of steam therefrom, an exhausting means for withdrawing condensate, unvaporized water and non-condensable gases from the radiators through the return pipe and lowering the pressure in the radiators, a valve at the inlet of each radiator for restricting the supply of heated water thereto, and means for automatically operating the valve in response to pressure changes in the radiator so that the pressure in the radiator will be lower than the pressure of the heated water by an amount sufficient to cause the water introduced into the radiator to expand into steam.
- 40 6. In heating apparatus, a source of heated water under pressure, a supply pipe leading from the source, a plurality of radiators, branch supply conduits leading from the supply pipe to each of the radiators, a return conduit having branches leading from each of the radiators, a steam trap at the outlet of each radiator to prevent the escape of steam therefrom, an exhausting means for withdrawing condensate, unvaporized water and non-condensable gases from the radiators through the return pipe and lowering the pressure in the radiators, a reducing valve in the conduit at the inlet to each radiator, and means for automatically operating the valve to maintain a predetermined pressure drop between the pressure of the heated water and the fluid pressure within the radiator. 80
- 45 7. In heating apparatus, a water heating device, a main pipe loop for circulating heated water from and back to the heating device, a plurality of radiators, branch pipes one leading from the pipe loop to each radiator, a pressure reducing valve in each branch pipe at the inlet to the radiator, a steam trap at the outlet of each radiator, an exhausting means for withdrawing condensate, unvaporized water and non-condensable gases from the several radiators and lowering the pressure therein, and means for automatically operating each reducing valve in response to relative pressure changes in the 90 radiator and branch pipe to maintain a predetermined pressure drop between the pressure of the heated water and the fluid pressure within the radiator. 95
- 50 8. In heating apparatus, a water heating device, a main pipe loop for circulating heated water from and back to the heating device, a plurality of radiators, branch pipes one leading from the pipe loop to each radiator, a pressure reducing valve in each branch pipe at the inlet to the radiator, a steam trap at the outlet of each radiator, an exhausting means for withdrawing water and non-condensable gases from the several radiators, lowering the pressure in the radiators, venting the gases, and returning the water to the heating device, and means for automatically operating each reducing valve in response to relative pressure changes in the 100 radiator and branch pipe to maintain a predetermined pressure drop between the pressure of the heated water and the fluid pressure within the radiator. 105
- 55 9. In a heating apparatus, a water heating device, a main pipe loop for circulating heated water from and back to the heating device, a plurality of radiators, branch pipes and a pressure control valve in each branch pipe at the inlet to each radiator for separately introducing the heated water in limited quantities from the circulating pipe into the several radiators, a thermostatic means acting on each valve to automatically cut off the flow of heated water to the radiator when a predetermined temperature has been reached in the space being heated by that particular radiator, a steam trap at the outlet of each radiator, and an exhausting means for withdrawing condensate, unvaporized water and non-condensable gases from the several radiators. 110
- 60 10. In heating apparatus, a water heating device, a main pipe loop for circulating heated water from and back to the heating device, a plurality of radiators, branch pipes and a pressure control valve in each branch pipe at the inlet to each radiator for separately introducing the heated water in limited quantities from the 115
- 65 11. In heating apparatus, a water heating device, a main pipe loop for circulating heated water from and back to the heating device, a plurality of radiators, branch pipes and a pressure control valve in each branch pipe at the inlet to each radiator for separately introducing the heated water in limited quantities from the 120
- 70 12. In heating apparatus, a water heating device, a main pipe loop for circulating heated water from and back to the heating device, a plurality of radiators, branch pipes and a pressure control valve in each branch pipe at the inlet to each radiator for separately introducing the heated water in limited quantities from the 125
- 75 13. In heating apparatus, a water heating device, a main pipe loop for circulating heated water from and back to the heating device, a plurality of radiators, branch pipes and a pressure control valve in each branch pipe at the inlet to each radiator for separately introducing the heated water in limited quantities from the 130
